UNITED STATES PATENT OFFICE.

GUS MAJOR KAISER, OF NEW YORK, N. Y.

BELT-BUCKLE.

1,087,065.

Specification of Letters Patent.

Patented Feb. 10, 1914.

Application filed April 3, 1913. Serial No. 758,585.

To all whom it may concern:

Be it known that I, GUS MAJOR KAISER, a citizen of the United States of America, residing at New York, in the county of New York and State of New York, have invented certain new and useful Improvements in Belt-Buckles, of which the following is a full, clear, and exact specification.

This invention relates to belt buckles and particularly to belt buckles which do not have a tongue or similar member requiring the belt proper to be provided with holes or perforations.

More specifically, my invention comprises a hollow casing, open at opposite sides for the passage therethrough of one end of the belt, and a pivoted cam member within said casing for holding the end of the belt in the desired adjusted position. I prefer to provide the pivoted cam member with a thumb piece or like externally projecting member, whereby to permit manual movement of the cam member to bring the same in contact with the belt proper, the securing or final holding position of the belt proper within the casing being effected automatically by the cam member.

My invention results in a belt buckle of marked simplicity and strength, and at the same time secures advantages of comfort to the wearer by nice adjustment of the belt; and also avoiding the necessity of puncturing the belt proper, and otherwise improving the ornamental features.

Other objects and features of my invention will be more fully understood from the following description, and the accompanying drawings, in which—

Figure 1 is a perspective view of a belt buckle embodying my invention, with certain of the hidden parts indicated in dotted lines; and Fig. 2 is a longitudinal cross-section of the same on a reduced scale, showing the positions of the parts when the belt is tightened.

The hollow casing member 1 comprises the front face 2, preferably of convex form. The opposite ends 3, 4 are open to allow the belt proper 5 to be passed therethrough, when it is desired to adjust the same about the body of the wearer. At one end of the belt buckle, such as extending from the open end 4 of casing 1, is provided the binding means 6 for fastening one end 7 of the belt 5. I have shown the fastening means 6 in the form of a cam having serrated teeth

for binding one end of the belt proper; however, any other form of binding means may be employed.

The cam member 8 comprises oppositely projecting end pivots 9, 10 passing through recesses in the transverse sides of casing member 1. From the pivots 9, 10, the cam member 8 comprises a portion 11 having the shape of a general curve, and a further portion 12 extending from the said portion 11, said portion 12 being corrugated, or otherwise roughened, such as by series of projecting edges, or the like. The thumb pieces 13, 13 are shown as extending from the portion 12 of cam member 8 through the arc slots 14, 14.

After one end 7 of the belt proper 5 has been fixed in the clamp 6, the other end of the belt proper is pushed through the opening 2, past the cam member 8 until it projects through opening 4. By grasping such projecting portion with one hand and the piece or pieces 13 with the thumb or other finger of the other hand to move the cam member toward the front face 2, the roughened portion 12 will be brought in contact with the belt proper, and upon slight longitudinal movement of the belt 5, the cam portion 12 will bind the same against the inner wall of the face 2. It will be noted that in such fastened position, the engagement of the portion 12 of cam member 8 is affected by means of a relatively large area with the coaction of a like area of the inner face of the front wall 2 of casing 1, this coaction being enhanced by the curved formation of face 2. By reason of such coöperation between the various parts, I have found that the cam member 8 may be formed of a general cross-section of C-shape, that is, a hollow construction having a portion of its periphery, or a side, opened, thereby securing lightness in weight, less cost in manufacture, without lessening the effectiveness of the buckle.

It will be observed that the point of junction of the portion 12 with part 11 of cam member 8 is of less radial distance from each pivot, and that the radial distances of the remaining portions or portion 12 increase gradually toward the free edge of portion 12. By this construction, it will be seen, the material of the belt may be made of different thicknesses within certain limits, and for any of such thicknesses the belt will be secured when in fastened position by the co-

action of relatively large areas of the cam member, the belt proper and the front face of the buckle casing.

It will be understood that the front face 5 2 of the buckle may be ornamented as may be desired.

Other changes and modification may be made in the specific form described without departing from my invention, as defined by 10 the appended claim.

Having thus described my invention, what I declare as new and desire to secure by Letters Patent of the United States is:—

A belt buckle comprising a hollow casing 15 member having a back, a slotted side, and a curved front, a transversely disposed C-shaped cam member composed of a single

sheet metal piece pivoted at the ends of one edge to said body, and having the surface of its engaging portion adapted to coöperate with said front, and an operating projection carried by one side of the engaging portion of said sheet metal member and movable in said slotted side of said body, said engaging portion of said clamping member being of progressively increasing distance from the pivot whereby to clamp varying thicknesses of material.

In testimony whereof I affix my signature in presence of two witnesses.

GUS MAJOR KAISER.
